PISTON

Donald J. Campbell, Spring Lake Township,
Ottawa County, Mich., assignor to Campbell,
Wyant and Cannon Foundry Company, Norton
Township, Mich., a corporation of Michigan

Application February 13, 1933, Serial No. 656,399
Renewed November 29, 1935

5 Claims. (Cl. 309—30)

The present invention relates to pistons for engine cylinders, particularly of the internal combustion type and more particularly of the Diesel type; and its object is to provide such a piston having improved means for preventing fluid leakage past the piston, especially in cylinders having great fluid pressure therein.

This and any other and more specific objects hereinafter appearing are attained by, and the invention finds preferable embodiment in, the illustrative piston structure particularly described in the body of this specification and illustrated by the accompanying drawings, in which:

Figure 1 is an elevational side view of a piston of an engine;

Figure 2 is an upper end view thereof;

Figure 3 is an axially sectional view of the same;

Figure 4 is a transaxially sectional view of portions thereof taken on line 4—4 of Figure 3;

Figure 5 is an elevational side view of a threaded ring part of the same;

Figure 6 is a lower end view of a portion thereof;

Figure 7 is an elevational side view of an annular part of the piston;

Figure 8 is an upper end view thereof;

Figure 9 is an elevational side view of a portion of the same;

Figure 10 is an elevational side view of a helical sealing element comprising mutually contacting members;

Figure 11 is an upper end view thereof.

In the embodiment of the invention illustrated by these drawings, a reciprocating piston for an engine cylinder is shown having the hollow cylindrical body or body member 1 provided with the usual bearing 2 for the wrist pin of the piston rod, the closed upper end 3 having angularly spaced strengthening ribs 4, etc. This body 1 has an annular recess 5 internally conical, or bevelled inwardly-downwardly in said body's radial directions, as particularly shown in Figure 3. An annular member 6 surrounding the body member has an annular lower end 7 conically formed correspondingly with said recess and bearing therein as indicated in said view. This annular member is expansible and contractible having the slip joint 8 as indicated in Figure 9. It will be seen that as said member 6 is moved downwardly on the piston's body it is diametrically contracted by the engaging of its conical lower end 7 with the correspondingly formed recess 5; and that it expands when moved upwardly.

A ring 9 is threaded at 10 on the piston body

and is turnable therearound to the position seen in Figure 3 wherein its inwardly extending flange 11 tightly contacts the piston body at 12 in fluid sealing relation. This ring 9 has a lower end or annular shoulder designated generally 13, and the piston body 1 is provided with an annular shoulder designated generally 14, said shoulder with which the piston body is thus provided being the upper edge of annular member 6. A sealing element, designated generally 15, surrounds the piston body between said shoulders 13 and 14 and is held thereby against movement axially of the piston.

This element 15 which sealingly contacts in inner surface of the engine cylinder to prevent fluid leakage past the piston, is shown of helical form, and as comprising a plurality of helical members, three such members 16, 17, 18 being shown in Figures 1, 3 and 10. These members helically engage each other being turned between and on each other to form the complete sealing element 15 as seen in Figure 10. The said element 15 engages at its upper end the correspondingly helically formed shoulder 13 of ring 9 and at its lower end engages the correspondingly helically formed shoulder 14 of the annular member 6. These shoulders comprise helical portions 19, 20, 21 on the ring 9 and 22, 23, 24 on the annular member 6, said portions being angularly spaced and being stepped apart to provide stops 25, 26, 27 on the ring and 28, 29, 30 on the annular member.

The upper ends 31, 32, 33 of the members of the helical sealing element abut on the respective stops of ring 9 and their lower ends 34, 35, 36 abut on the stops respectively of the annular member 6 respectively, which operates as a tension equalizer therefor.

By reason of the helical formation of the sealing element 15 and of its members, the edges thereof in sealing contact with the cylinder are inclined from planes to which the piston's and the cylinder's axis is perpendicular. The result is that the reciprocation of the piston causes said element's edges to move the lubricating oil not only in the direction of the piston's reciprocation but also in a direction inclined therefrom, thus better distributing the oil around the cylinder's inner surface. This action also tends to prevent scoring of the cylinder.

The annular sealing element is shown provided with a longitudinal channel 37 filled with a solid lubricant 38, as graphite composition or the like.

As the ring 9 is screwed down, the members 16,

- 17, 18 of the helical sealing element 15 are pressed into sealing contact with each other and with the shoulders 13, 14, and as the pressure of the ring increases on said element the annular member 6 is forced down farther into the recess 5, being diametrically contracted in such movement; and as the ring 9 is turned reversely, the annular member 6 is permitted to expand by its resiliency.
- 10 It is contemplated that the ring 9, when turned to properly adjusted position, may be fixed therein as by the set screw 39 threaded in said ring and seating in a socket 40 in the upper end of the piston body. In such adjusted position, any 15 expansion or contraction of the piston body in its axial direction caused by the heating or cooling thereof or by the heating or cooling of one part or one end thereof more rapidly than the heating or cooling of other parts or the other 20 end of the piston body, will not seriously affect said element's sealing function. Nor will the heating or cooling of other parts seriously affect such function. As this helical sealing element 15 heats it expands lengthwise, i. e. in its helical 25 direction thus turning by said stops the annular member 6, against friction, in the recess 5, and said member is also pressed downwardly in the recess 5 and thus contracted; but as the sealing element 15 cools and contracts, the said annular 30 member expands by its resiliency and rises. The provision of a plurality of members of the sealing element 15, with their ends angularly spaced equally apart, renders the action of said element more uniform around the piston and cylinder.
- 35 The heating and cooling of the parts compensate or offset each other, for as the piston body expands by heating, the space between said shoulders increases and the sealing element 15 (including its members) also expands lengthwise thus taking up such increased distance between 40 the shoulders, and the annular member 6 also expands and moves upwardly.

The invention being intended to be pointed out in the claims, is not to be limited to or by 45 details of construction of any particular embodiment thereof illustrated by the drawings or hereinbefore described.

I claim:

1. An engine piston comprising: a body provided with a shoulder comprising helical portions 50 stepped to provide stops therebetween; a ring threaded on the body provided with an annular shoulder comprising helical portions stepped to provide stops therebetween; a helical sealing element surrounding the body between the shoulders comprising helically engaging members having 55 ends abutting a stop of the body portion and a

stop of the ring respectively, and being pressed into sealing relation with each other, with the shoulders and with the cylinder.

2. An engine piston comprising: a body provided with a shoulder comprising helical portions 5 equally angularly spaced and stepped to provide stops therebetween; a ring threaded on the body provided with a shoulder comprising helical portions equally angularly spaced and stepped to provide stops therebetween; a helical 10 sealing element surrounding the body between the shoulders comprising helically engaging members having ends abutting a stop of the body portion and a stop of the ring respectively, and being pressed into sealing relation with each 15 other, with the shoulders and with the cylinder.

3. An engine piston comprising: a body member; a compressible-expansive annular member surrounding the body member and having a helical portion and a stop, one of said members having 20 a conically formed annular end portion and the other one of said members having a correspondingly formed annular recess receiving said end portion; a helical sealing element surrounding the body member; an element having a helical 25 portion and a stop, and secured to said body member in sealing relation therewith; said helical sealing element being in sealing relation with said helical portions and stops.

4. A piston for engines comprising a piston body 30 provided with an annular shoulder at the head end thereof and a threaded portion adjacent said shoulder and an annular conical shoulder axially spaced from said threaded portion; an 35 annular ring embracing the said threaded portion, the said annular ring being provided with transverse abutment shoulders; a split ring positioned against the annular conical shoulder provided with transverse abutment shoulders; and a plurality of helical sealing elements 40 surrounding the piston body between the aforesaid annular and split rings and supported in sealing position thereby by the axial shoulders thereof.

5. A piston for engines comprising a piston 45 body; an annular ring shouldered on the body and threaded thereto, the said ring being provided with a plurality of axially spaced shoulders; a split ring shouldered on the piston body and spaced from the annular ring, the said split 50 ring being provided with a plurality of transverse shoulders; and a plurality of helical packing rings supported in flexible sealing relation against the cylinder wall by the transverse shoulders of the said annular ring and of the split 55 ring.

DONALD J. CAMPBELL.
